UNITED STATES PATENT OFFICE

CHARLES WILLMER MITCHELL, OF MORENCI, ARIZONA

GAUGING BLOCK FOR DRILL-BIT-SHARPENING MACHINES

Application filed June 14, 1928. Serial No. 285,461.

The present invention relates to gauging blocks used in connection with the manufacture of rock drill bits and has for its principal object to provide an adjustable means for regulating the size of the bit while crimping the same by the sharpening machine.

A still further object is to provide a pair of cooperating gauging blocks adapted to form the bit to an accurate diameter after the same has been dollied and formed to shape.

A still further object is to provide a gauge of this character designed for use particularly in connection with the Leyner drill bit sharpening machine.

An additional object of this invention is to provide a device of this character of a simple and practical construction, which is strong and durable, efficient and reliable in performance, which is readily adjustable to form the bit into various sizes of a relatively wide range, which is relatively inexpensive to manufacture and install in operative position and otherwise well adapted for the purpose for which the same is intended.

Other objects and advantages reside in the special construction, combination and arrangement of parts forming the invention as more fully hereinafter described and claimed, reference being had to the accompanying drawings forming part hereof, wherein like numerals refer to like parts throughout, and in which:

In the drawings:

Figure 1 is a fragmentary side elevational view of a sharpener machine showing the gauge in operative position thereon,

Figure 2 is a rear end elevational view of the box comprising the gauge,

Figure 3 is a top plan view of the lower gauge box,

Figure 4 is a vertical transverse sectional view taken substantially along a line 4—4 of Figure 1, and

Figures 5 and 6 are perspective views of the upper and lower gauging blocks.

Referring now to the drawing in detail, whereas for the purpose of illustration I have disclosed a preferred embodiment of my invention, the numeral 5 illustrates the table of

a drill steel sharpening machine, such as the well known Leyner machine and above which is disposed the punch head 6 operatively mounted on the plunger 7 and connected with a suitable source of power for moving the punch head downwardly toward the table. Upon the table 5 is arranged an index bar 8 of substantially U-shaped formation as shown in Figure 3 of the drawing, said index bar being disposed in horizontal position and with its closed end projecting slightly outwardly from the edge of the table and having its parallel sides 9 provided with longitudinally extending slotted openings 10.

Within each of the slotted openings is arranged an adjusting bolt 11 having their inner ends threadedly inserted in openings formed in the opposite side edges of a lower clamping block 12 secured against the outer face of the table 5 by a bolt 13. The clamping block 12 is thus fixedly attached to the table and by reason of the bolt 11 extending outwardly from the opposite side edges thereof and carried in the slotted opening 10, the index bar 8 may thus be adjusted inwardly or outwardly with respect to the table 5.

The inner upper edge of the clamping block 12 is formed into a reduced shoulder 14 adapted to form a support for an extension 15 formed at the upper edge of one end of a lower gauge block 16. The opposite end of the gauge block 16 is provided with a pair of dowel pins 17 adapted to seat within recesses formed in an abutment 18 extending upwardly from the table 5 inwardly from the edge thereof.

The gauge block 16 is of a substantially wedge shaped formation with its lower surface resting upon the table 5 and its upper surface inclined downwardly and inwardly. The inner end of the gauge block 16 is disposed flush with the inner end of the U-shaped index bar 8.

To the outer edge of the punch head 6 is secured an upper clamping block 19 by a bolt 20, said upper clamping block serving to secure an upper gauge block 21 to the under side of the punch head 6. The inner end of the upper gauge block 21 is also provided

with a pair of dowel pins 22 seated in recesses formed in an abutment 23 depending from the under side of the punch head.

The outer lower edge of the upper gauge block 21 is formed with an extension 24 disposed immediately beneath the upper clamping block 19, and said upper gauge block is likewise of a substantially wedge shaped formation with its lower surface inclined upwardly and inwardly.

The upper and lower gauge blocks 16 and 21 are of a duplicate formation and are secured to the machine in a manner so that their inclined faces will engage the opposite sides of the flared end of the drill bit 25. The bit engaging faces of the gauge block, adjacent their outer edges are concaved as shown at 26 for accommodating the shank of the bit so that the entire portion of the bit disposed between the gauge block is engaged at opposite sides by the respective blocks. These gauge blocks are removable for interchangeably mounting other blocks provided with concavities of various sizes to accommodate bits of various diameters.

The upper edge of the index bar 8, at the outer end thereof, and the upper edge of the lower clamping block 12 are likewise concaved as shown at 28 and 29 respectively to also accommodate the shank 27. At the inner end of the index bar 8 is arranged a bit stop 30 arranged to engage the center of the inner end of the bit 25, said bit stop being adjustably mounted on a substantially U-shaped yoke 31 invertedly arranged and with its opposite ends sliding vertically within recesses formed in the upper surface of the opposite end of the index bar 8.

The yoke 31 thus extends transversely of the lower gauge block 16 and the bit stop is arranged for sliding movement upon the yoke 31 so as to provide for the transverse adjustment of the stop with respect to the sides of the index bar. The bit stop may be secured in adjusted position by a set screw 32.

The yoke 31 is secured in vertically adjusted position by set screws 33 threaded in the index bar and engageable with the respective ends of the yoke. The stop may thus be readily adjusted for centering the same with respect to the bit. The upper surface of each side of the index bar 8 is provided with a scale 34 cooperating with a set mark 35 formed on the upper edge of the lower clamping block 12 for adjusting the index bar and as a consequence the bit stop whereby to regulate the position at which it is placed between the gauge block for crimping the same to a predetermined size, for shaping and forming the length and degree of the flared portion at the inner end of the bit. It is understood that when placing the invention in practice that the end of the steel desired to be treated for a distance of approximately five inches of the length thereof is heated to a forging heat.

It is obvious that my invention is susceptible to various changes and modifications in construction without departing from the spirit of the invention or the scope of the appended claims, and I accordingly claim all such forms of the device to which I am entitled.

Having thus described my invention, what I claim as new is:

1. A bit gauging attachment for bit sharpening machines comprising a pair of clamping blocks attachable respectively to the table and punch head of the machine, gauging blocks removably secured in bit crimping position by said clamping blocks and having seats of predetermined capacity, a U-shaped index bar, means for adjustably mounting the same on one of said clamping blocks, a bit stop carried by said index bar, means for adjusting said bit stop vertically and transversely with respect to said index bar for centering the stop with respect to the bit.

2. A bit gauging attachment for bit sharpening machines comprising a pair of clamping blocks attachable respectively to the table and punch head of the machine, gauging blocks removably secured in bit crimping position by said clamping blocks and having seats of predetermined capacity, a horizontally disposed, U-shaped index bar, means for adjustably mounting the same on one of said clamping blocks providing for the adjustment thereof relative to the gauging block, a bit stop, an invertedly arranged U-shaped supporting yoke for said bit stop having its ends supported at the inner end of said index bar, means for vertically adjusting said yoke with respect to said bar, and means for transversely adjusting said bit stop on said yoke transversely of said bar for centering the stop with respect to the bit.

In testimony whereof I affix my signature
CHARLES WILLMER MITCHELL.
